UNITED STATES PATENT OFFICE.

JOHN W. CULP, OF JOHNSTOWN, PENNSYLVANIA.

MECHANICAL GAME TOY.

Application filed March 17, 1927. Serial No. 176,033.

My invention relates to a mechanical game toy somewhat similar to the roller type disclosed in my co-pending application for Letters Patent of the United States of America, bearing filing date the 25th day of February, 1927, and Serial No. 171,032.

The primary object of the invention is to provide a device of the type stated, which is operable to provide an entertaining and amusing game mainly dependent on the element of chance for designating one or several indicia adaptable for determining scores, counts, positions and a multiplicity of other purposes applicable thereto.

Further objects of the invention are to provide a device of the character described which is very simple in its construction and arrangement, strong, durable and efficient in its use, attractive in appearance, compact, positive in its action, and comparatively inexpensive to manufacture.

To the accomplishment of these and such other objects as may hereinafter appear the invention consists of the novel construction and arrangement of parts hereinafter described and claimed, it being understood that changes, variations and modifications thereof may be resorted to that come within the scope of the claims hereunto appended.

In the drawing wherein like numerals of reference designate corresponding parts throughout the several views:—

Figure 1 is a front end view of the toy constructed in accordance with the invention.

Figure 2 is a side view thereof, partly in cross section.

Figure 3 and Figure 4 are respectively front end and side views of a modified form of the device.

Referring in detail to the drawing 1 denotes a hollow, cylindrical body portion including a permanently fixed rear end plate 2, and an annular rim 3 fixed to the forward end thereof. The rim 3 is formed with an inwardly disposed annular flange 4 which frictionally engages and detachably secures the inset front or cover plate 5 mounted in the rim 3. The construction of the body portion 1, the end plate 2, the rim 3 and the inset front plate 5, are identical in construction to the ordinary sheet metal can now commonly employed as containers for many products. The outer face 6, of the front

plate 5, is inscribed to provide a dial, which is divided into like areas 7, by equally spaced, radially extending lines 8. The latter are connected at respective ends by a pair of circular lines respectively, indicated at 9 and 10. Seven areas 7 are provided and each is inscribed with an indicia 11. The latter consist of numerical designations from "zero" to "seven" arranged in sequence relatively to the arrangements of the areas 7.

It will, of course, be obvious that the number and arrangement of such area divisions and the arrangement of the indicia may be widely varied to meet any conditions found in practice, without departing from the spirit of the invention.

An indicator member 12 is disposed on the outer side of the front plate 5 and is pivotally mounted to always maintain its perpendicular suspension, by means of a pivoting pin 13. The latter is fixed in the diametric center of the front plate 5 and projects forwardly from the latter.

The indicator member 12 is provided with a main finger 14 which is disposed above its point of suspension and with a pair of spaced auxiliary fingers 15, which is disposed below its point of suspension. The weight of that portion of the indicator member 12 which is disposed below the point of suspension is greater than that portion of the indicator member 12 which is disposed above the point of suspension, whereby the natural action of gravity will invariably maintain the perpendicular disposition of the indicator member 12.

The distance between the auxiliary fingers 15 is greater than the length of the areas 7, so that at least one of the pair of fingers 15 must inevitably designate one of the areas 7 even if the other of the pair of fingers 15 registers with one of the division lines 8. The main finger 14 may designate an area 7 or may register with one of the division lines 8.

In practice the body portion 1 is rolled along a floor or any other surface by the impetus imparted thereto by the player. After the rolling operation the indicia 11 designated by the main finger 14 or by the pair of auxiliary fingers 15 are credited to the player in accordance with any predetermined rules or regulations provided in connection therewith.

A shiftable weight 16 may be placed in the body portion 1 for the purpose of rendering the rolling operation less susceptible to determination by the skill of the player. The 5 shiftable weight 16 may consist of one ball, as illustrated, or of a number of balls or sand, or any other material that is shiftable within the body portion. If desired, the 10 body portion 1 may be formed with a suitable slot (not shown) for the passage of coins, thereby accommodating the device for use as a depository for coins, with the latter serving as the weight for the purpose herein stated.

The modification of the device illustrated 15 in Figures 3 and 4, of the drawing, is identical in construction and operation to the preferred form hereinbefore described, with the exception that the body portion 17 instead of being cylindrical is polygonal shaped in 20 transverse cross section. While this construction will somewhat impede the rolling of the device, the body portion 1 will invariably seat on one of the flat sides 18, thereof, when at rest. By providing the body portion 17 with an unequal number of sides 18, and associated angles or corners 19, the latter will always be disposed upwardly when the body portion 17 is at rest. The front cover plate 5 is preferably so arranged in the 30 body portion 17, that the dial radial lines 8 extend radially relatively to the center of respective flat sides 18, as clearly shown in Figure 3. By this arrangement of the front plate 5, the main finger 14 of the indicator member 12 will always designate an indicia 11 and will register with any of the radial lines 8.

The device is preferably fancifully colored 40 to make same ornamental and attractive in appearance, and while primarily intended to serve as a game toy, the device may be readily utilized as an advertising specialty by pro-

viding same with characteristics adaptable for such purposes.

It will be noted that the outer end of the 45 end plate 5 is disposed forwardly of the indicator member 12 whereby the latter is protected against potential injury during the use of the device.

What I claim is:

1. In combination, a mechanical toy of the character described comprising a hollow cylindrical body portion provided with a fixed rear end plate, an inset cover plate detachably secured to the front end of said body portion, the front face of said cover plate provided with a dial divided into equal areas, each of said areas having a designating indicia, an indicator member pivotally connected to said cover plate at the diametric center 60 of the latter, said indicator disposed flatly against the outer side of said cover plate, and embodying means for maintaining the same perpendicularly suspended by gravity, and a spherical weight member loosely disposed in 65 said body portion.

2. In combination, a mechanical toy of the character described comprising a hollow cylindrical body portion provided with a fixed rear end plate, an inset cover plate detachably secured to the front end of said body portion, the front face of said cover plate provided with a dial divided into equal areas, each of said areas having a designating indicia, an indicator member pivotally connected to said cover plate at the diametric center 70 of the latter, said indicator disposed flatly against the outer side of said cover plate, said indicator embodying a plurality of fingers for 75 simultaneously designating a series of said 80 dial areas and for maintaining said indicator perpendicularly suspended by gravity.

In testimony whereof I affix my signature.
JOHN W. CULP.
